PAPER BOX SEALING

Filed May 14, 1928

UNITED STATES PATENT OFFICE

JOHN B. VAN WORMER, OF TOLEDO, OHIO, ASSIGNOR TO THE AMERICAN PAPER BOTTLE COMPANY, OF TOLEDO, OHIO, A CORPORATION OF OHIO

PAPER-BOX SEALING

Application filed May 14, 1928. Serial No. 277,415.

This invention relates to containers, especially of sheet material.

This invention has utility as a single service receptacle for liquids as milk.

5 Referring to the drawings:

Fig. 1 is a perspective view, with parts broken away, of an embodiment of the invention as a milk bottle or container;

10 Fig. 2 is a view of the closure for the container of Fig. 1 in open position;

Fig. 3 is a fragmentary view of the container closure with the tuck-in-tongue so assembled, with the supplemental wrapper not bent over such tongue as yet;

15 Fig. 4 is a section on an enlarged scale on the line IV—IV, Fig. 1; and

Fig. 5 is a view of the blank for the container of Fig. 1.

In the instance shown, sheet stock as 20 per may be taken in providing blank having container sides 1, 2, 3, 4, with connecting flap 5 therefor to form such into a tube. Bottom 6 is supported by bottom sections 7, 8, with outer bottom seat 9 therefor. This car- 25 ton blank or container is desirably of water- proofed or paraffin-coated stock, when the substance to be carried is a liquid as milk. The substance of the container is essentially one which is not soluble by the contents at 30 normal temperatures. This closed end tube is provided with top closure including opposing rectangular sections 10, 11, intermediate triangular major sections 12, 13, having connecting triangular portions 14. The rectan- 35 gular sections 10, 11, are approximately of half closure extent, and thus similar to the bottom sections 7, 8. Continuous beyond this series of rectangular sections 10, 11, and tri- angular sections 12, 13, 14, is extension band 40 15. This band 15 has beyond the rectangular section 10, tuck-in-tongue extension 16, and beyond the rectangular section 11, supple- 45 mental flap 17 terminating in wings 18 as a wrapper.

45 In the use of this container, it may be set up as to closing either top or bottom before charging with the contents. In the event the top is first closed, the bottom is sealed thereon, while in the event the bottom closure be 50 the one first sealed, then the top closure is

the one to be sealed thereafter when the container is charged with its contents say of milk. In the instance the bottom closure be first sealed, the sealing may be supplemented by a paraffin coat, or the container be given 55 an initial paraffin coating. As thus sealed in assembly with the insoluble coating as to the contents, the top closure as a tube extension with the band 15 continuous, may be opened to receive the charge of milk say as pre-measured in a machine. The tubular extension top closure is then collapsed, which collapse is initially as shown in Fig. 2. Further progress of this collapsing permits insertion of the tongue 16 back of the band portion 15 as 60 adjacent the triangular sections 14 and with the tongue adjacent the band portion as 65 above the rectangular section 11.

In practice, a most effective double sealing is obtained under the invention herein 70 by dipping the tongue 16 and supplemental flaps 17, 18, or even up to the band 15 in the coating material just prior to the charge of the milk into this container. Accordingly, 75 with this coating adherent but not fully set, the insertion of the tongue 16 between the folded band portion above the section 14 and adjacent the band portion above the section 11 brings about a cohesion between these sections and the tongue which is a primary 80 sealing to be supplemented by folding over of the supplemental flap 17 to be adjacent the band portion 15 as carrying the tongue 16. Thereafter the supplemental flap 18 85 may be wrapped to the opposite side of this projecting reinforcing rib of the closure to be adjacent the band 15 as above the section 11 and mounting this supplemental flap or wrapper 17. Accordingly the fold over of this flap 17 is the supplemental sealing with 90 the flap extension 18 coating as adhering against the band 15 for locking the wrapper in the supplemental sealing assembly.

95 This doubly sealed rib closure permits the container in itself to have a reliable seal reinforcement against fracture and of such stability that the rib may serve as a handle. In packing or nesting these containers, there is thus clearance provision therebetween allowing for temperature expansion disturb- 100

ances as avoiding rupture of the containers. In practice, the container may be opened by jabbing a tool therethrough.

What is claimed and it is desired to secure by Letters Patent is:

5 A container comprising an end closure, a pair of opposing rectangularly defined sections, connecting intermediately triangularly defined sections, said rectangular and triangular sections terminating in a continuous band extension with additional supplemental extensions beyond said band for the rectangular sections, the band portions intermediate the rectangular sections being foldable between the band portions at the rectangular sections, one of said supplemental extensions coacting as a tuck-in-tongue from its rectangular section band portion over the folded band portions from the 10 intermediate sections in a container closure rib-forming assembly and the other extension from its band portion foldable over the tuck-in-tongue and against the band portion for said tongue coacting as a seal there- 15 over, and additional sealing effecting holding means coacting between the opposing 20 portions of the continuous band.

25

In witness whereof I affix my signature.

JOHN R. VAN WORMER.
